VENTILATING DEVICE

Louis J. Jenn, Minneapolis, Minn.

Application May 11, 1940, Serial No. 334,541

4 Claims.

(Cl. 98—29)

This invention relates to a ventilating device and particularly to such a device adapted to draw fresh air from the exterior of a wall into a room or to move air from a room to the outside thereof.

It is desirable in many rooms in business places and residences, particularly such rooms as kitchens, to have the air moved therefrom to keep the atmosphere in a fresh condition and to eliminate odors. It is desirable to have a simple, efficient and inexpensive device which can be placed in an opening in a wall of a room so that air may be drawn into or removed from said room and it is desirable to have such a device which can be placed in position for closing said opening when ventilation is not desired.

It is an object of this invention, therefore, to provide a simple and efficient ventilating device which can be produced and installed at comparatively small expense and which can be used to draw air into or force air from a room and which further is arranged to close the opening from said room when not in use.

It is another object of the invention to provide a device comprising a casing adapted to be disposed in an opening through the wall of a room, a member mounted in said casing having a passage therethrough which can be positioned to form a passage through said casing and wall or which can be turned to close the opening in said casing, said member carrying means for moving air through said passage.

It is more specifically an object of the invention to provide a ventilating device comprising a casing adapted to be disposed in an opening through the wall of a room, a member mounted in said casing for rotation about a vertical axis having a passage therethrough, said member having comparatively thick portions at the sides of said passage whereby said passage may be disposed transversely of the wall to afford a passage therethrough or may be disposed substantially parallel to said wall so that said thick portions will close the opening through said casing and wall, said member having a motor and fan driven thereby mounted thereon and disposed in said passage.

These and other objects and advantages of the invention will be fully set forth in the following description made in connection with the accompanying drawings in which like reference characters refer to similar parts throughout the several views and in which:

Fig. 1 is a view in front elevation of said de-

vice showing a portion of the wall in which it is disposed;

Fig. 2 is a central vertical section through the device shown in Fig. 1;

Fig. 3 is a horizontal section taken substantially on line 3—3 of Fig. 2 as indicated by the arrow;

Fig. 4 is a partial view in rear elevation of the device, some parts being broken away and others shown in vertical section;

Fig. 5 is a view similar to Fig. 3 showing the parts in a different position;

Fig. 6 is a horizontal section taken substantially on line 6—6 of Fig. 1 as indicated by the arrows; and

Fig. 7 is a vertical section taken substantially on line 7—7 of Fig. 6 as indicated by the arrow.

Referring to the drawings, a device is shown comprising a casing 10. Casing 10 is constructed and arranged to be disposed in an opening in a wall illustrated as 11, which may be an outside wall of a room. While casing 10 could be formed of various materials, in the embodiment of the invention illustrated it is shown as formed of sheet material, such as sheet metal and having a top wall 10a engaging the top of the opening through wall 11 and a bottom wall 10b engaging the bottom of the opening through wall 11. Said casing has a front side 10c shown as substantially flush with the inner side of wall 11 and said casing has a rear wall 10d shown as substantially flush with the outer side of wall 11. Strips or blocks 9 are disposed in the corners of casing 10 and the front wall 10c and the rear wall 10d are formed as separate and removable plates and secured in position by screws 9a which extend therethrough into blocks 9. A member 12 is disposed in casing 10, said member being illustrated as in the form of a cylinder having a vertical axis. Member 12 is carried on and secured to a bracket 13 disposed at the bottom thereof, screws 14 securing said bracket and member together. Bracket 13 is carried on and rotatable on another bracket 15 having a bearing thereon and while various types of bearings might be used, in the embodiment of the invention illustrated bracket 13 is shown as having a hub with a flat lower end resting on the flat top surface of bracket 15. Bracket 15 is secured to lower wall 10b by circumferentially spaced headed and nutted bolts 16 and said bracket has a central hub 15a extending through and some distance below lower wall 10b. Bracket 13 is secured to a shaft 17 extending centrally therein by a pin 18, said

shaft extending downwardly through hub 15a. Member 12 has a passage 12a extending centrally therethrough and while this passage might be variously formed, in the embodiment of the invention illustrated it is shown as cylindrical. Passage 12a when disposed with its axis extending transversely of wall 11 affords a passage through casing 10 and said wall as shown in Figs. 1 to 3. Casing 10 has a front opening 10e and a rear opening 10f. The front wall 10c of casing 10 has forwardly projecting portions 10g in the form of segments of a cylinder which extend outwardly and surround or enclose the top and bottom portions of member 12. Rear wall 10d has similar portions 10g which extend outwardly and surround or enclose the upper and lower portions of member 12. Member 12 has extending therethrough in spaced relation vertical rods 20, the same being headed and provided with nuts at their lower ends, said heads and nuts engaging washers or blocks 21 of resilient material disposed at the outer sides of member 12. Rods 20 have flattened portions 20a intermediate their ends and bolts or screws 22d extend through the portions 20a and into lugs 22a extending from the casing of a motor 22, which motor is of the electrical type. Motor 22 is thus carried by and secured to rods 20. Motor 22 has its armature shaft 22b projecting at the side thereof opposite rods 20 and a fan 24 has a hub 24a bored to fit on shaft 22b, the same being held on said shaft by a set screw 25. It will be noted that the blades 24b of fan 24 are shaped to extend along the sides of motor 22. A conductor cable 26 is shown as extending from motor 22 through the bottom of member 12 and the flange of bracket 13.

The casing 10 will preferably be disposed adjacent the ceiling of the kitchen or other room in which it is disposed. Shaft 17 is shown as extending downwardly some distance below casing 10 and a bracket 30 is shown secured to the inner side of wall 11 by screws 31. A small gear or pinion 32 is secured to shaft 17 in any suitable manner as by pin 33, said pinion meshing with a gear segment 34 mounted upon a headed stud 35 secured in a bracket 36 which is in turn secured by screws 37 to an inwardly projecting platelike portion 30a of bracket 30. Screws 37 are shown as headed and extending through a slot 30b in portion 30a so that some adjustment of bracket 36 lengthwise of said slot is permitted. Bracket 36 has a hub 36a receiving the lower end of shaft 17. A U-shaped member 38 having its bite portion concentric with segment 34 is secured to bracket 36 by screws 39, blocks of insulating material 40 being disposed between the ends of member 38 and bracket 36. As shown in Fig. 7 member 38 is offset upwardly at its inner portion from bracket 36. A contact arm 41 is secured by screw 42 to segment 34, a block of insulating material 43 being disposed between member 41 and segment 34. Member 41 is offset upwardly and has a downwardly extending contact member 41a adapted to engage with contact portions 38a on member 38. Members 38 and 41 thus form a switch for controlling the circuit of motor 22. Suitable conductors 45 and 46 are secured to members 38 and 41 and will extend to motor 22 and the line respectively. Member 34 has a handle portion 34a which projects outwardly through an opening 30c in bracket 30. Bracket 30 and thus handle 34a will be disposed so as to be conveniently accessible to a person standing on the floor of a room. A hood 48

shown as formed from sheet material, such as sheet metal, is secured to the outer side of wall 11 and extending about casing 10. Hood 48 has a flange 48a secured to wall 11 by screws 49. A suitable gear may extend across opening 10e, the same being indicated in section in Fig. 3.

In operation, when it is desired to move air out of the room the device will be in the position shown in Figs. 1 to 3. At this time contact 41a 10 will engage one of the contact portions 38a and handle 34a will be substantially at one limit of its movement. Passage 12a is aligned with the 15 openings 10e and 10f of casing 10 so that a passage extends through wall 11. Motor 22 will be 20 driven and fan 24 will thus be driven and air will be moved from the room through passage 12a to the outside. If it is desired to draw fresh air from the outside into the room the operator 25 can swing handle 34a and rotate pinion 32 through substantially 180 degrees, thus rotating shaft 17 and member 12 so that fan 24 is disposed adjacent the outer side of wall 11. Fan 24 will then draw air into the room through 30 passage 12a. It will be noted that member 12 has quite thick portions at the sides of passage 12a and member 12 can be disposed in an intermediate position as shown in Fig. 5 so that the 35 portions at the sides of passage 12a close the openings 10e and 10f of casing 10. The openings 40 through casing 10 are thus closed off and air cannot pass either way through casing 10 and wall 11. The member 12 can be made of good insulating material and casing 10 may contain insulating material thereabout so that there 45 will be substantially no heat loss from the room when member 12 is in the position shown in Fig. 5. It will also be readily seen that member 12 could be disposed in various positions between the position shown in Fig. 5 and that shown in 50 Fig. 3 so that only a portion of passage 12a aligns with the openings 10e and 10f. The volume of air passing into or out of the room can thus be regulated by disposing member 12 in different positions. It will also be noted that fan 24 is 55 quite accessible from one end of member 12 and can readily be removed from shaft 22b if desired by loosening screw 25. Cable 26 will, of course, be of sufficient length so as to permit and not interfere with the oscillation of member 12. The 60 blades 24b which are partially disposed at the sides of motor 22 will act to cool said motor in the rotation of said fan. Hood 48 protects the 65 device from rain or snow.

From the above description it is seen that I 70 have provided a simple and efficient ventilating device. The same can be made of small size and easily and inexpensively installed in the wall of a room. The device is constructed so that it will form an efficient closure for the ventilating opening when it is not in use. The exterior of member 12 can be nicely finished and if desired may harmonize with the wall as can also casing 10 so that the device is inconspicuous when in closed position. The device can easily be kept 75 clean. When the device is in closed position the motor and fan are well protected in passage 12a. The device has been amply demonstrated in actual practice and found to be very successful and efficient.

It will, of course, be understood that various changes may be made in the form, details, arrangement and proportions of the parts, without departing from the scope of applicant's invention, which generally stated, consists in a device capable of carrying out the objects above

set forth, in the parts and combinations of parts disclosed and defined in the appended claims.

What is claimed is:

1. A ventilating device for a room having in combination, a casing adapted to be disposed in an opening through a wall of said room and having inner and outer openings at opposite sides thereof disposed adjacent opposite sides of said wall, a second substantially cylindrical casing disposed in said casing and mounted for rotation therein about a central axis, said second casing having a passage extending therethrough and being rotatable through substantially 180 degrees so that the ends of said passage can be positioned adjacent either of said inner or outer openings in said first mentioned casing, said second casing also having portions between the ends of said passage closing said openings in said first mentioned casing when said second casing is in mid-position, a motor and fan driven thereby mounted in said passage in said second casing whereby said second casing may be moved into one position with said passage aligned with said first mentioned openings so that air will be drawn into said room by said fan or may be positioned in another position with said passage aligned with said openings so that said motor will discharge air from said room or may be placed in mid-position closing said first mentioned openings.

2. A ventilating device for a room having in combination, a casing substantially rectangular in form adapted to be disposed in an opening through a wall of said room and having an inner opening adjacent one side of said wall and an outer opening adjacent the other side of said wall thus forming a passage through said wall, a second casing disposed in said first mentioned casing and mounted for rotation therein, said second casing having a passage extending therethrough, the ends of which may be brought adjacent the openings in said first mentioned casing, said second casing having portions between the ends of said passage adapted to close said openings in said first mentioned casing, a motor

5 mounted in said second mentioned casing in said passage, a fan carried by and driven by said motor, a shaft supporting said second casing for rotation in said first mentioned casing, means carried by said first mentioned casing supporting said shaft, said second casing being rotatable through 180 degrees so that it can be positioned with said passage aligned with said first mentioned openings and said motor and fan positioned to draw air into said room or it may be positioned with said passage aligned with said openings and said motor and fan positioned to discharge air from said room or it may be positioned midway between said positions to close said first mentioned openings.

10 3. The structure set forth in claim 8, means for rotating said shaft and a switch for said motor simultaneously operated by said last means.

20 4. A ventilating device for a room having in combination, a casing adapted to be disposed in an opening through a wall of said room and having inner and outer openings at opposite sides thereof disposed at opposite sides of said wall, a second casing disposed in said casing and mounted for rotation therein, said second casing having a passage therethrough and portions between the ends of said passage adapted to close or partially close said first mentioned 25 openings, a motor mounted in said second casing, a fan carried by said motor and means for rotating said second casing through substantially 180 degrees so that it can be positioned with said passage extending between said first mentioned openings with said motor and fan in position to draw air into said room, so it can be positioned with said passage extending between said openings and said fan and motor disposed to discharge air from said room, so it 30 can be disposed midway between said positions to close said first mentioned openings or so that it can be placed in intermediate positions to partially close said first mentioned openings.
